(57) **CLAIM**

We claim the ornamental design for a frame for a magnifier, as shown and described.

DESCRIPTION

FIG. 1 is a perspective view of a frame for a magnifier showing our new design;

FIG. 2 is a top plan view of FIG. 1;

FIG. 3 is a right side elevational view of FIG. 1;

FIG. 4 is a left side elevational view of FIG. 1;

FIG. 5 is a first end elevational view of FIG. 1;

FIG. 6 is a second end elevational view of FIG. 1; and,

FIG. 7 is a bottom plan view of FIG. 1.

The dotted lines are intended to show features that are environmental only and form no part of the claimed design.
